UNITED STATES PATENT OFFICE.

WALTER H. KNIGHT, OF NEW YORK, N. Y.

ELECTRIC RAILWAY.

SPECIFICATION forming part of Letters Patent No. 338,081, dated March 16, 1886.

Application filed July 10, 1885. Serial No. 171,187. (No model.)

To all whom it may concern:

Be it known that I, WALTER H. KNIGHT, a citizen of the United States and a resident of the city of New York, N. Y., have invented 5 certain new and useful Improvements in Electric Railways, of which the following is the specification.

My invention consists in a device for guiding the depending contact apparatus in an electric railway into either one of two branches.

In the accompanying drawings, Figure 1 represents a plan view of the branching slot. Fig. 2 is a view of the conduit with the top removed, and Fig. 3 shows the contact apparatus.

In a patent granted to me September 23, 1884, No. 305,731, I have shown a contact apparatus depending from an electric locomotive into a slotted conduit, to maintain an electric connection between the said locomotive and the main conductors inclosed in the said conduit. This apparatus or "plow," as it is termed, is shown in Fig. 3, and consists, as is described in said patent, of a metallic 20 guard-frame extending into the slot and carrying a panel of insulating material in which are embedded the conductors with contact-springs at their lower ends. The guard-frame both protects the insulated conductor from 25 wear and injury, and gives it a rigidity against bending in any direction as it passes along the conduit.

Whenever it is necessary that a branch of the railway described in the said patent be employed, it is of course necessary that the conduit should also be branched, and some means should be employed for guiding the contact apparatus into either branch of the conduit. Such means are shown in Fig. 1. 30 a represents the slot of the main conduit, and b and c represent the slots in the two branching conduits, respectively. C represents the guide-piece, pivoted at the branching-point P. This guide-piece is normally held in the position indicated by the full lines by means of a 35 spring, S, which acts upon the tail-piece A, forming a continuation of the guide-piece beyond the point P, and when in this position it closes the slot b and leaves a substantially 40 clear passage from the slot a into the slot c.

The lower edge of the guide-piece is beveled, and the plow H is pointed at either end, as

shown in Fig. 1. When, therefore, the plow, moving in the direction of arrow k, passes from the slot a into the slot c, it strikes the 55 lower edge of C and thrusts it to one side, should the passage be not quite clear; or the spring may normally hold the guide centrally over the slot, and be always thrust in a definite direction by the plow striking the bevel. 60 In passing from slot b to slot a the plow will encounter the guide-piece C, as is shown in Fig. 1, and will thrust it aside against the pressure of the spring S into the position indicated by the dotted lines. Thus the guide-piece being held in a fixed position by means of the spring, the passing plow will be deflected 65 in a definite direction. This is of special value in turn-outs where the switches of the track are always set so as to guide a vehicle 70 in a definite direction—for example to the right, as in Fig. 1.

In Fig. 2, A B are the two main conductors, suspended upon insulating-pins from the walls of the conduit substantially in the manner described in my said patent. A' B' are the conductors in one branch, and A² B² are the conductors in the other branch. The positive conductors are connected by bridge-wire E throughout, and the negative conductors are 80 connected by bridge-wires F. The plow being guided by the slot-piece, the contact shoe or brush, which may be used in lieu of the spring-contact of my patented plow, (shown in Fig. 3,) carried by said plow will also be guided 85 thereby in the proper direction.

I have shown in Fig. 2 a contact-brush, and it is of sufficient length to bridge the space between the positive conductor A A' and the branch conductor A², so that the connection 90 will be maintained while the plow is passing from the main to the branch conduit. A corresponding contact-brush will be employed for the negative conductor.

I am aware that beveled guide-plates adapted to be automatically operated by the contact device have been heretofore used with tubular conductors. The guide-plates as claimed in my invention, however, are upon the conduit inclosing the conductors.

Having thus described my invention, what I claim is—

1. The combination, in a branching electric railway, of conduits along the main and branch

tracks, respectively, an insulated longitudinal conductor in each conduit, a protected insulated conductor adapted to extend into either main or branch conduit and having a contact device adapted to make a traveling connection with said longitudinal conductor in either conduit, but detachable therefrom, and a movable guide-piece for the slot at the branching-point of said conduit.

o 2. The combination, in a branching electric railway, of a main and branch conduit, a longitudinal insulated conductor in each conduit, a movable guide-piece adapted to close the entrance to one branch of the conduit, and an insulated contact-conductor adapted to extend into either main or branch conduit with a protecting-guard, whereby it is adapted to actuate said guide-piece.

3. The combination, with a branching slotted conduit, of beveled guide-plates C, spring S, adapted to hold said guide-plate over the branching-slot, and a protected insulated conductor adapted to extend into either branch of the conduit and to actuate said guide-plate.

25 4. The combination of the main conductor A, a branch conductor, A', forming a continuation of A, a branch conductor, A², connected with A and A', and the contact device of a length sufficient to bridge the break between A, A', and A².

30 5. The main conductor A, branch conductor A', forming a continuation of A, branch conductor A², connected to A A', but placed so as to allow the passage of the contact device, combined with a contact device adapted to pass from A A' to A² without interruption of the contact.

6. The combination, in an electric railway, of a slotted conduit, a stationary insulated electric conductor therein parallel with the slot and adapted to carry the actuating current for an electrically-propelled vehicle upon the railway, a branching slotted conduit hav-

ing also a stationary insulated conductor parallel with the slot and in line with the conductor in said main conduit, a contact device extending into said conduit and adapted to move along the conductor in either conduit, and a movable guide-piece for said device placed at the branching-point of the conduit.

45 50

7. The combination, in a branching electric railway, of a branching slotted conduit, an insulated longitudinal conductor in the main and in each branch conduit, a conductor extending into the conduit with a spring reacting thereon and acting to press a contact against said longitudinal conductor, and a movable guide-piece for the conduit at the point of branching.

8. The combination of the branching slotted conduit, an insulated conductor inclosed in each branch thereof, a rigid insulated conductor extending through the slot with a contact device at its lower end, and a movable guide for the said rigid conductor at the branching-point of the slot.

9. The combination, with a main slotted conduit and an insulated conductor therein, and a contact device connected with a vehicle and extending into said slot to make connection with said conductor, of a branch conduit having a slot leading into the slot of the main conduit, and an insulated conductor therein leading to the main conductor at the point of junction of the two slots and adapted to the said contact device, whereby the contact device may pass from main to branch slot and from the main conductor to the conductor in the branch conduit.

In testimony whereof I sign this specification, in the presence of two witnesses, this 30th day of June, 1885.

WALTER H. KNIGHT.
